TRAVELING CASE FOR GARMENTS

Frederick K. Bauer, P.O. Box 1705,
Beverly Hills, Calif. 90213

Filed May 13, 1974, Ser. No. 469,222

Term of patent 14 years

Int. Cl. D3—02

U.S. Cl. D87—1 R

Fig. 1

Fig. 2

Fig. 4

FIG. 1 is a side perspective view of a traveling case for garments showing my new design, the opposite side being substantially similar and with the center zipper extending substantially across the case in the same manner as the end zippers;

FIG. 2 is an elevational view thereof in slightly relaxed position;

FIG. 3 is a bottom plan view; and

FIG. 4 is a top perspective view thereof in a flat folded over and secured condition.

I claim:

The ornamental design for a traveling case for garments, substantially as shown and described.
